United States Patent Office.

JOSEPH TRENT, OF MILLERTON, NEW YORK.

Letters Patent No. 69,511, dated October 1, 1867.

IMPROVEMENT IN CAR-COUPING.

The Schedule referred to in these Letters Patent and making part of the same.

TO ALL PERSONS TO WHOM THESE PRESENTS SHALL COME:

Be it known that I, JOSEPH TRENT, of Millerton, in the county of Dutchess, and State of New York, have invented a Combined Self-Acting Coupling and Buffer for Railway Cars; and do hereby declare the same is fully described and represented in the following specification and the accompanying drawings, of which—

Figure 1 is a top view representing my invention as applied to two railroad trucks.

Figure 2 is a sectional elevation, and

Figure 3 an under side view of same.

Figure 4 is a horizontal section of my combined coupling and buffer.

Figure 5, a vertical section of same.

Figure 6 represents a face view of one of the buffers, with its screw and sliding-block for retaining the self-operating catch in position.

Figure 7, a face view representing the opposite buffer, with its screw-rod and latch for maintaining the self-operating catch in place; and

Figure 8, a view representing one of the trucks thrown off from the railroad track, and my invention in the act of disengaging itself and disconnecting the trucks.

This invention relates to a novel contrivance for coupling and disengaging railroad cars, in which the coupling is self-acting, that is to say, will engage itself, and when so engaged will be held in such position by dropping a latch or block against the face of the catch or connecting-link holder; and when it is desired to disengage the cars, the brakeman merely raises the block or latch, when the cars will be disengaged, and will remain disengaged, and will not engage themselves while standing on the track, (as is the case with other devices,) until the block or latch is again lowered, and this performance is accomplished by the brakeman, while standing on the platform of the car, without resorting to the dangerous and often fatal expedient of going between the trucks to perform the operation.

Furthermore, should one or more cars, while in rapid motion, run off the track, they will immediately disengage themselves without the aid of the brakeman, as shown in fig. 8; and, besides this, the strain or pressure caused by the cars abutting against their buffers when starting or braking up a train of cars, is not sustained by the framework of the cars or trucks, as is usual in such cases, but by the buffer-bars which abut against an India-rubber spring placed between the extreme ends of the buffer-bars, as shown in fig. 3.

Having described the nature of my invention, I will now describe its construction and mode of operation.

In the drawings, A A' represent two railroad trucks; B B', the buffers; b, the connecting-link; C C', the link-catches, which swing on pivots e e in the buffer-mouths, and are so arranged as to maintain a vertical position by their own gravity. D D' are the buffer-bars, which are sustained by and slide in suitable bearings, d d, below the floor of the trucks A A', and between the braces a a of the same, as shown in fig. 3. The said buffer-bars have journals, e e, on their outer ends for reception of the buffers or buffer-mouths, and nuts or collars f f for the purpose of retaining the buffers B B' in position, while they (the buffers) revolve on their journals. G or G' is the block or latch, which is operated by the screw-rod H or H'; and by its agency the block G is lowered against the face of the catch C, when it is desired to connect the coupling, and raised from the catch C when it is desired to disconnect the same, as already explained.

The operation of my invention is very simple, and is as follows: When it is desired to connect the rail cars, the brakeman, while standing on the platform of the car, lowers the block or latch G by means of the screw-rod H against the face of the link-catcher C, (the other block G' being already lowered, and the link b thereby held in position,) the said catchers being now in a position to receive and retain the link b, which, as the cars approach each other, said link will push the tail end of the catcher C forward till the eye of the link b passes said tail end, when the catcher will drop into the eye of the link, and prevent the release of the link until the block or latch G is again raised from the face of the catcher C; and while the cars are thus firmly connected together, should one or more of the cars run off the track while the train is in rapid motion, the coupling will, in this case, disengage itself, for the buffers, being so arranged as to turn on their journals, one of the buffers will only require to make a quarter turn, (in relation to the other,) when the catch C or C' will be moved away from the block G or G', and the coupling disengaged, as shown in fig. 8. Furthermore, in relation to removing the strain

or pressure caused by the buffers abutting against each other, in starting or braking up a train of cars, from the framework of the cars to the buffer-bars, it will be observed that the buffer-bars D D' slide freely within their bearings d d, and their inner ends abutting against the India-rubber springs K K', the whole pressure is brought to bear on the said rubber springs, and thus removed from the framework of the cars.

From the above it will be seen that I have designed a simple and efficient coupling, which will be a great saving of expense as regards the wear and tear consequent on the strain and pressure of railway cars, as well as a saving of human life.

Having described my invention, what I claim, and desire to secure by Letters Patent, is—

The combination and arrangement of the revolving buffers B B', buffer-bars D D', blocks G G', springs I K', and rods H H', substantially as described for the purpose specified.

In testimony whereof I have hereunto set my signature.

JOSEPH TRENT.
